Attorney

UNITED STATES PATENT OFFICE

CLAUDE W. FOSTER, OF BRADFORD, PENNSYLVANIA, ASSIGNOR TO NATURAL FLUID LIFT COMPANY, OF BRADFORD, PENNSYLVANIA, A COPARTNERSHIP

FLUID LIFT

Application filed February 2, 1928. Serial No. 251,393.

This invention relates to a fluid lift and it is an object of the invention to provide a mechanism for this purpose wherein is eliminated the use of heavy tubing rods, working barrels, heavy pull lines and the like and thus obviating the expense of installation and maintenance of equipment of such kind.

It is also an object of the invention to provide a lift embodying an endless member extending downwardly a requisite distance of the bore and which member is constructed in a manner to provide a plurality of buckets whereby the fluid, upon requisite travel of the endless member, is lifted to the surface.

Another object of the invention is to provide a mechanism of this kind wherein the lifting member initially discharges within an enclosed tank and which is of particular advantage when the lift is employed in connection with an oil well, said tank serving to confine the gas and thereby maintaining the well from drying out and paraffining up.

The invention consists in the details of construction and in the combination and arrangement of the several parts of my improved fluid lift whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a view partly in section and partly in elevation illustrating a fluid lift constructed in accordance with an embodiment of my invention and in applied assembly;

Figure 2 is a fragmentary elevational view of the endless lifting member;

Figure 3 is a sectional view taken substantially on the line 3—3 of Figure 2;

Figure 4 is a sectional view taken substantially on the line 4—4 of Figure 2.

As disclosed in the accompanying drawing, B denotes a bore drilled to requisite depth and which has arranged in its upper portion

only a desired length of tubing T. The casing T, as herein disclosed, is operatively engaged with the well head 1 which constitutes the bottom of an enclosed tank A. The walls of this tank A including the head 1 may be made of any material which is believed to best comply with the requirements of practice.

In communication with the tank A through the top wall 2 thereof is a gas line 3 and also in communication with the tank A through a side wall 4 thereof and preferably immediately adjacent to the head 1 is a fluid carry-off line 5. The casing T extends a desired distance above the head 1, as herein disclosed, and threaded or otherwise connected to such projected portion of the tubing is an upstanding sleeve 6 of desired length. This sleeve 6 at substantially diametrically opposed points is provided with the brackets 7 rotatably carrying the tension rollers 8 for the endless lifting member M.

The member M, as herein disclosed, comprises two endless strips 9 of belting maintained in desired spaced relation by the interposed endless strips 10 arranged at the longitudinal marginal portions of said strips 9. Also interposed between the strips 9 are the transversely disposed members 11 bridging the space between the strips 10 whereby the spaces between the strips 9 and members 11 are divided into a plurality of successively arranged buckets.

The outermost strip or belting 9 has disposed along its longitudinal or side marginal portion the strips 12 which have direct contact with the tension rollers 8 and thus preventing such rollers from exerting undue pressure on the buckets or imposing undue wear or tearing action upon the outer strip 9 or belting 9.

Each of the buckets formed in the member M at one end is provided with a transversely disposed opening 14 affording access to the associated bucket whereby as such bucket is passing through the fluid in the bore B the same will readily fill and as the bucket is turned over above the ground surface, the same will be readily emptied.

The endless member M is disposed around

a roller or drum 15 of desired diameter rotatably supported by opposed side walls of the tank A and at a desired point above the sleeve 6. Stretches of the endless member extend downwardly through the applied casting T to the lower portion of the bore B. The lower portion of the member M passes under a pulley 16 rotatably supported by a yoke 17 straddling the lower portion of the member M from below and depending therefrom. The lower portion of the yoke 17 carries a weighted member 18 whereby requisite strain is imposed upon the stretches of the applied member M to assure the requisite travel thereof with respect to the fluid within the bore B and also to maintain said member M in desired tractive or frictional engagement with the roller 15.

The roller 15 may be driven in any desired manner but, as herein disclosed, is shown as being in driven connection through the medium of the belt 19 with an engine E which may be of an electrical explosive type or otherwise as preferred. This roller 15 is fitted on a shaft 15' which projects exteriorly of the tank A, the belt 19 being operatively engaged with said shaft exteriorly of the tank A.

It is to be noted that the upwardly traveling stretch of the applied member M has the openings 14 in communication with the upper portion of the buckets so that the fluid within the lower portion of the bore B will be readily carried upwardly and, as such buckets pass around the roller 15, the same will readily discharge within the tank A and the fluid in the tank A may be readily carried off through the pipe line 5.

When my improved lift is being employed in connection with oil wells, the tank A is a further particular advantage as it serves to confine the gas from the well and thereby keeps the well from drying out and paraffining up.

From the foregoing description it is thought to be obvious that a fluid lift constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

A fluid lift comprising an endless member consisting of two endless strips, second endless strips interposed between the side longitudinal portions of the first named strips to maintain said first strips in spaced relation, additional strips interposed between the

first named strips and bridging the space between the second named strips, said last named strips dividing the space between the first named strips into a plurality of buckets, one of the first named strips having openings, 70 each of said openings being in communication with an end portion of a bucket.

In testimony whereof I hereunto affix my signature.

CLAUDE W. FOSTER.
